COMBINATION LIFT FORK AND BARK STRIPPER FOR AN END LIFT VEHICLE

John W. Rycraft, Klamath, Calif.

Filed June 12, 1967, Ser. No. 7,429

Term of patent 14 years

(Cl. D14—3)

FIG. 1 is a side perspective view, taken slightly from the front, of the combination lift fork and bark stripper embodying my design;

FIG. 2 is a side elevational view of the same;

FIG. 3 is a top plan view of the same;

FIG. 4 is a side elevational view, the fragmentary portion of the vehicle upon which it is mounted being shown in broken lines for illustrative purposes only.

I claim:

The ornamental design for a combination lift fork and bark stripper for an end lift vehicle, substantially as shown and described.
